WOMAN'S OVERSHOE

Duncan E. Slade, Naugatuck, Conn., assignor to United States Rubber Company, New York, N.Y., a corporation of New Jersey

Filed Sept. 22, 1961, Ser. No. 66,805

Term of patent 14 years

(Cl. D7—4)

FIG. 1.

FIG. 2.

FIG. 3

FIG. 1 is a side perspective view of a woman's overshoe showing my new design. The broken line showing of a shoe is for illustrative purposes only;

FIG. 2 is another side perspective view of the overshoe; and

FIG. 3 is a bottom plan view thereof.

The side of the woman's overshoe opposite to that shown in FIGS. 1 and 2 is substantially identical thereto.

I claim:

The ornamental design for a woman's overshoe, as shown and described.
